UNITED STATES PATENT OFFICE.

THOMAS WHEATLEY, OF SYRACUSE, NEW YORK.

AIR-VALVE FOR RADIATORS.

SPECIFICATION forming part of Letters Patent No. 759,052, dated May 3, 1904.

Application filed April 16, 1903. Serial No. 152,888. (No model.)

To all whom it may concern:

Be it known that I, THOMAS WHEATLEY, of Syracuse, in the county of Onondaga, in the State of New York, have invented new and useful Improvements in Air-Valves for Radiators, of which the following, taken in connection with the accompanying drawings, is a full, clear, and exact description.

This invention relates to certain improvements in radiator-valves for permitting the escape of air and preventing the exit of the heating fluid, and refers more particularly to that class in which the water of condensation or other liquid heating agent is partly collected in a suitable well and a float is partially immersed in the liquor in the well and operates a suitable valve to close the air-vent.

This device is similar in some respects to that set forth in my application of even date herewith, Serial No. 152,889, filed April 16, 1903, but differs therefrom by having a double-walled well in which the float is movable, the double wall forming an air-chamber which surrounds the well proper and communicates therewith.

The primary object of this construction is to trap the air in a chamber by the same liquid in which the float is immersed, so that the heating agent impinges against the inner and outer walls of said chamber, and thereby permits the use of an open or a closed float, and also operates expansively to close the float through the medium of the liquid into which the float is immersed.

Further objects will be brought out in the description which follows.

In the drawings, Figure 1 is an elevation of a radiator-valve embodying the features of my invention. Figs. 2, 3, and 4 are sectional views taken, respectively, on lines 2, 2, Fig. 1, and 3, 3 and 4, 4, Fig. 2. Figs. 5 and 6 are perspective views of the detached well and float seen in Fig. 2, and Fig. 7 is a perspective view of a slightly-modified form of float having an open end.

This device consists, essentially, of an outer shell 1, an inner receptacle or well 2, and a float 3, the shell 1 being provided with an inlet-opening 4 in its base and with an outlet or vent

opening 5 in its opposite upper end. The well 2 is suspended within the shell 1 between the inlet 4 and outlet 5 and preferably consists of two cup-shaped parts 6 and 7, arranged one within the other, the outer cups being of less diameter than the inner diameter of the shell 1 and is provided with an imperforate bottom 8, while the inner cup is of less diameter than the inner diameter of the outer cup, and its upper end is open and united to the upper end of the outer cup for permanently closing the latter and forming an air-chamber 9. The bottom of the outer cup terminates in a plane above the inlet 2 to form a subchamber 9' in the base of the shell 1, whereby the inflowing heating agent impinges directly against the full area of said bottom, and the upper end of the well is formed with laterally-projecting shoulders 10, which are separated from each other to form passages 11. The bottom wall of the inner cup 7 is disposed above the bottom wall of the outer cup and separated therefrom and is provided with a substantially central opening 12, whereby the water flowing into the open upper end of the inner cup is conducted into the base of the outer cup, and thus compresses or traps the air in the chamber 9.

The float 3 is arranged centrally in the inner cup 7 and is preferably of less diameter than the inner diameter of said cup, so as to be free from contact therewith, both ends being closed and are provided with outwardly-projecting stems 13 and 14, the former serving as a valve to close the air-vent 5, and the latter is movable in the opening 12 and prevents undue lateral movement of the lower end of the float. It is evident, however, that the lower end of this float may be open, as seen in Fig. 7, in which instance it is provided with a transverse bar 16, having a projecting stem 17, the latter being adapted to move in the opening 12 to guide the lower end of the float.

It will now be seen that the heating agent passing through the inlet 2 first impinges against the bottom wall of the outer cup or well and then passes upwardly between the outer shell and well and through the passages 11, so as to entirely envelop the well and float,

the water being precipitated into the inner cup and is discharged therefrom into the base of the outer cup. This seals the air in the upper portion of the outer cup, so that when said air is heated it acts expansively on the liquid in the well and causes the liquid to rise in the inner cup, thereby causing the float to rise and close the air-vent 5. The passage for the heating fluid being subdivided by the shoulders 10, it is apparent that the volume of water is broken up, whereby an instantaneous circulation is induced the instant the valve closes, and the water will therefore flow unimpeded back into the radiator. This segregation of the body of water which may accumulate in the outer shell is further augmented by an additional deflector-plate 15, which is provided with suitable projections 18 and passages 19, the projections 18 serving to engage 20 the lower end of the well and prevent its lateral displacement.

Having thus described my invention, what I claim, and desire to secure by Letters Patent, is—

- 25 1. In an air-valve for radiators, an outer shell having an inlet and a valved outlet, a well in the outer shell having two concentric walls connected to form an air-trap, a float in the well and operatively connected to actuate the valve.
- 30 2. In an air-valve for radiators, an outer shell having an inlet and a valved outlet, a well comprising two cups in the shell one within the other, the inner cup being united to the outer cup to form an air-chamber and communicating at or near the bottom whereby the water first enters the inner cup and then enters the outer cup to compress the air in said chamber, and a float in the inner cup operated by the expansion of the air in said

chamber to close the valve through the medium of the water.

3. In an air-valve for radiators, an outer shell having an inlet and a valved outlet, a well suspended in the outer shell free from its base 45 and having an inner water-receiving chamber, and an air and water chamber communicating with the lower end of the water-chamber, and provided with an imperforated top to trap the air and a float in the well for operating the 50 valve.

4. In an air-valve for radiators, an outer shell having an inlet and a valved outlet, a double-walled well in the outer shell forming an air-chamber between the walls, the inner 55 wall having an opening at or near its bottom, and a float in the well to operate the valve.

5. In a radiator air-valve, an outer case or shell having an inlet and an outlet, a well comprising two cups, one within the other, and 60 united at the top to form a chamber closed at its upper end, and the inner cup having openings in both ends, a valve for the outlet, and a float in the inner cup operatively connected to close the valve.

6. In a radiator air-valve, an outer shell having an inlet and a valved outlet, a well comprising two cups of unequal diameter in the shell one within the other, the outer cup having an imperforate bottom and united to 70 the inner cup to form an air-trap, and the inner cup communicating with the interior of the outer cup, and a float in the inner cup connected to actuate the valve.

In witness whereof I have hereunto set my hand this 13th day of April, 1903.

THOMAS WHEATLEY.
